UNITED STATES PATENT OFFICE

2,319,205

ELECTRICALLY OPERATED TOOTHBRUSH

Foster Buck, Lisle, Ill.

Application April 3, 1939, Serial No. 265,637

3 Claims. (Cl. 128—41)

This invention relates to electrically operated tooth brush mechanism.

Electrically operated tooth brushes of the portable or hand type have long been known and numerous types and constructions have been proposed. Because of cumbersomeness, cost, and for various other reasons, none of them has met with sufficient approval to bring such an article into general use by the public.

An important object of the present invention is the provision of a simple, inexpensive electrically operated tooth brush which is effective for the cleansing of the teeth and the massaging of the gums.

Another object of the invention is the provision of an operating mechanism which is responsive to the exertion of pressure against the tooth brush as an incident to the normal use of the tooth brush.

A still further object of the invention is the provision of a novel casing or housing for the operating unit of the tooth brush mechanism.

Further and important objects of the invention will become clear from a consideration of the drawing wherein a preferred embodiment of the invention is illustrated and more fully described and wherein:

Figure 1 is a plan view showing the general appearance of the tooth brush device of my invention.

Figure 2 is a longitudinal sectional view, partly in elevation.

Figure 3 is a sectional view taken along the line 3—3, looking in the direction of the arrows.

Figure 4 is a perspective view showing the vibrator unit.

Figure 5 is a fragmentary view, partly in section, showing a modified form of my invention which is adapted for use with direct current.

In general, the electrically operated tooth brush of the present invention comprises a casing or housing within which is mounted the means for causing movement of the tooth brush. In the preferred embodiment, this means comprises an electromagnet made up of a core and windings therefor. A pivoted arm, preferably made of a mild steel, is provided which is adapted to be vibrated and to which a tooth brush is adapted to be operatively connected so as to vibrate with said pivoted arm. The pivoted arm is provided with an armature portion, preferably of soft iron, which, in normal and inoperative position, is essentially in contact with an extended part of the core. When the core windings are connected to a suitable source of electric current, the device,

as stated, is inoperative. However, when pressure is exerted against the tooth brush, for example, by urging the same against the teeth, the armature, which is attached to the pivoted arm and which is, in turn, operatively connected to the tooth brush, moves away from contact with the core, and the tooth brush then vibrates.

The casing is of the bi-part type and comprises two complementary sections of essentially similar construction. Each of these sections is provided on its inner surface with a relatively short, narrow upstanding rib, preferably formed integrally with said sections, which is adapted frictionally to engage a side of the vibratory arm so that, although there is no interference with the vibration of the arm within the relatively narrow amplitude within which it moves, the casing sections lock together without the necessity for any additional means. In order to prevent too ready dis-assembly of the device, however, I prefer to use additional fastening means such as screws or the like as seen more particularly in the drawing.

As is shown clearly in Figure 2, the device comprises a casing 10, within which is mounted the operating mechanism. In its preferred form, this comprises an electromagnet comprising a cylindrical core 11 and a coil or windings 12, the windings being covered with an insulating layer 13 of paper or the like. Insulating discs 14 and 16 of fiberboard or the like are provided as shown. An arm 17, having side members or arms 18 and 19, is attached to the core 11 by means of a screw 21 or the like which passes through a spring washer 22 and is threaded into the core. The arm 17 is of resilient metal and is pivotally mounted so that it may vibrate within a narrow amplitude as indicated in dotted lines in Figure 2.

Between the sides 18 and 19 of the arm 17 is an armature block 23, preferably made of soft iron, a screw 24 or the like being used to attach the same to the arm. The block 23 normally is maintained in essential contact with a flattened portion 26 on the core 11 when the windings therefor are connected to a source of alternating current or the like. In this position, the device is in inoperative position, that is, the arm 17 remains stationary. Attached to the side member 18 in any suitable way as, for example, by means of a screw 27 is a tooth brush stem or holder 28 which serves to detachably hold a tooth brush 29, the latter being firmly but removably held in an opening or aperture therein preferably by friction. The brush stem 28 passes through a relatively soft rubber or like grommet 31 which

allows vibratory movement of the stem when the device is operated. A cord 32 leading to a source of electric current is attached to the coil or windings 12 on the disc 16.

The casing 10, as shown in Figure 3, is made up of two complementary sections 33 and 34. Each of these sections is provided on its interior surface adjacent one side with a relatively narrow and thin upstanding rib 36. When the core and coil assembly with its vibratable arm 17 is assembled in the casing, the ribs 36 project somewhat, from opposite sides, between the inner surface of the arm 17 and the periphery of the coil 12. The engagement is frictional but does not in any way interfere with the vibratory movement of the arm 17 when the device is in operation. The result is that when the sections 33 and 34 of the casing 10 are secured together as a unit, the arm 17 and associated apparatus are held in place without the necessity of employing additional fastening means. Nut and bolt assemblies 37 and 38 are employed to secure the casing sections 33 and 34 together.

The operation of the device is believed to be clear from the foregoing description. When the coil is connected to a source of alternating or pulsating current, the device does not function although current is flowing through the coil. However, when the tooth brush is pressed against the teeth to initiate the cleaning operation, the movement of the armature block 23 away from contact with the core 11 causes the arm 17 to vibrate and this, in turn, causes the vibration of the tooth brush. It will be seen that the movement of the tooth brush is in a direction which is at right angles to the longitudinal axis of the core although the plane of movement is in line with the longitudinal axis of the core.

In the illustrative embodiment of my invention as disclosed in the drawing, the device is operated by alternating or pulsating current. If it is desired to adapt the mechanism for operation also from a source of direct current, this may be accomplished by an interrupter means which can be mounted within the casing 10 as indicated in Figure 5. As there shown, contact buttons 39 and 41, mounted on arms 42 and 43, respectively, are attached to the core 11, flattened on opposite sides as shown, by means of a screw 44 or the like, insulating washers 46, 47 and 48 being utilized to separate the arms 42 and 43. The contacts 39 and 41 are connected in series with the coil and a source of power such as an ordinary commercial line. Conveniently, one lead 40 from the coil 12 is connected to the arm 42 and the other lead 45 from the coil 12 connected to a commercial power source. A conductor 50 is connected to the arm 43 and is also connected to the opposite side of the line. The arm 43 is extended and abuts against the lower end of an insulating member 49 which is attached to the side 18. It will be seen, therefore, that when the armature block 23 is in contact with the core 11 the contact buttons are spaced apart and the circuit is incomplete. However, when pressure is exerted against the tooth brush as an incident to the use of the device, the mem-

ber 48 is elevated and the contact buttons 39 and 41 meet whereupon current flows and the tooth brush is set into motion. Arms 42 and 43 are connected in series with the coil.

5 What I claim as new and desire to protect by Letters Patent of the United States is:

1. The combination of a casing and an electrically operated tooth brush mechanism or the like, the operating mechanism of which includes a vibratable arm, said casing comprising essentially similar complementary sections which are adapted to form a relatively tight enclosure, the inner surface of each of said sections being provided with a relatively short, narrow upstanding rib which is so constructed and arranged as to frictionally engage one side of said pivoted, vibratable arm of the operating mechanism and positive fastening means to secure the complementary sections together as a unit whereby when the complementary sections are secured together as a unit the mechanism of which the vibratable arm forms a part may be held in position without the necessity for additional fastening means, the parts being so constructed and arranged as to permit movement of said vibratable arm when the operating mechanism is in operation.

2. In combination with an electrically operated tooth brush mechanism, an electromagnet comprising a core and windings therefor, a pivoted arm adapted to be vibrated, a part of said arm being essentially in contact with at least a part of said core when said windings are connected to a source of electric current, the arm being inoperative in such position, a toothbrush carried by said arm a bi-part casing within which said mechanism is enclosed, the inner surface of each part of said casing being provided with a narrow, upstanding rib which is so constructed and arranged as to frictionally engage a side of said pivoted arm, and positive fastening means to secure the complementary sections together as a unit whereby when the casing is held together as a unit the electrically operated mechanism of which said arm forms a part is secured in flexed relation to said casing without the necessity for additional fastening means, the parts being so constructed and arranged as to permit movement of said vibratable arm away from contact with said core by the exertion of pressure against the tooth brush whereupon the arm is set into vibration.

3. An electrically operated vibrating tooth-brush device which is adapted to operate on direct current comprising an electromagnet comprising a core and windings therefor, a pivoted arm adapted to be vibrated, a part of said arm comprising an armature which is in essential contact with a part of said core, the device being inoperative in such position, a brush carried by said pivoted arm, said armature being responsive to movement of said brush in operative engagement with a work surface, such as the teeth, and a pair of contact members which are open when the device is in inoperative position but which are adapted to close responsive to the movement of the armature away from contact with the core.

FOSTER BUCK.
